" The Greenleaf

Collins Patent

The subject is referred to in these Collins Patent and making part of the same containing a description in the words of the said "The Greenleaf" himself of his improvement in the Notary Motor Engine.

Full & true it may concern. So it is known that of the Greenleaf have invented his certain improvements in the Notary Motor Engine and that the following is a full and exact description of the same; reference being had to the accompanying drawings. A tight is the inside of the cylinder within which the valves and piston operate A.A. Fig 2 is a section of the same, part B.B. Fig 1 are valve chambers to receive the valves at the cylinder head, and part C.C. are the piston chambers in section i.e. one in valves one of which is shown as raised the other as closed.

The cylinder turns upon a shaft D.D. made of wood this shaft is turned perfectly true and is slightly raised in the part which passes through the cylinder and the collar which surrounds it between the valve chambers.

It is thus made for the purpose of accurately fitting the rod bearing part to it as by raising or lowering this part it may be made to run like a tight without packing and without binding. I adjust it when it runs horizontally there can never be piping through the collar D which is supported by the uprights C.C. the mode of adjustment being adopted when the position is changed. The valves C.C. are shown fitted to them which pass through stuffing boxes in the top of the valve chambers. The valve chambers have the packing being closely fitted against the shaft and sliding in going up and down in the cylinder in which they fit. These tight are made to fit at its mid and edge. The valves are raised and lowered by means of a guide formed around a cylinder or upon the rim of a wheel to which gear with a direction is given as shall be best adopted to produce the effect intended.

This wheel is turned & these are friction rollers which slide in the grooves to avoid the wearings which would otherwise take place. The motor is admitted through the shaft by the main pipe B and is then stopped

through which operation of these openings being similar to them in some other rotary Engines. Fig 3 is a section of the shaft of the piston, and of the lever or arm which it turns by which the piston is first turned. As the whole body of the rotary Engines is intended to have some vertical play upon the shaft it is necessary that the piston should also be movable. This end is attained by allowing some play to the shanks of the screws by which it is attached to the arm or lever.

Fig 4 is a side view of the piston. Towards the shaft D an opening is shown: this is intended to receive packing between its back end and the shaft which packing is secured by plates of metal turned over it on one side. Fig 5 is an end view of the piston which is made in two pieces as shown by the lines thereon. This is for the purpose of regulating its width with perfect precision: the tenth line near the upper part represents a pin of metal through which regulating screws work: their points bearing upon the parts A & M, and their heads bearing in the upper plate. Besides the plate of metal, other elastic packing may be interposed between the two parts. The manner of putting this piston together may be varied and the same end attained namely the adjusting it to the chamber but in all it forms the manner of attaching it to the lever or back end of screw play. Thereon is an essential feature of my invention.

I have described the cylinder as revolving and the shaft as stationary but the intelligent mechanist will perceive that all its operation, features may be preserved and the revolving motion given to the shaft when such a variation may be proposed. That I claim as my invention is the conical form given to that part of the shaft upon which the cylinder revolves for the purpose of admitting them to each other without packing: the attaching the piston to the lever in such a way as give it play enough to adapt itself to the chamber of the cylinder. The manner of forming the piston in parts so as to adjust it to the cylinder and the particular manner in which the valves are made to slide through the head of the cylinder into the valve chambers. Small variations may be made in the foregoing structure whilst the principles upon which it acts remain unchanged. Thus for example there may be a greater number of valves and pins. The valve chambers may be placed on the ends of the cylinder opposite to that described and a plate or head put over the cylinder at right angles with the shaft dividing the main chamber into two parts: pistons attached to levers or

valves formed upon and operating on the principle described being attached thereto, the steam being admitted into and escaping from such chamber as with the single piston. These may of course best be the piston and valve located in such a chamber to admit the steam to all parts of the shaft at the same time. Provision may also be made for admitting steam through other openings for the purpose of instantaneously decreasing the motion when required.
